UNITED STATES PATENT OFFICE.

THOMAS S. CULP, OF CANTON, OHIO.

DESIGN FOR A BICYCLE-FRAME.

SPECIFICATION forming part of Design No. 27,438, dated July 27, 1897.

Application filed April 3, 1897. Serial No. 630,653. Term of patent 14 years.

To all whom it may concern:

Be it known that I, THOMAS S. CULP, a citizen of the United States, residing at Canton, in the county of Stark and State of Ohio, have 5 invented and produced a new and original Design for Bicycle-Frames, of which the following is a specification, reference being had to the annexed drawing, forming a part thereof.

In the drawing the figure is a perspective 10 view of my design.

The leading feature of my design is the peculiar formation of the frame illustrated in the drawing.

The bars 1 extend rearward in a straight 15 line to a point where the rear axle is to be located, and back of that point bent inward toward each other, forming the **U** portion 2, the bars or tubes are bent upward, forming segments of circles. From the connecting 20 portions 3 lead the tubes 4 upward and forward, forming the **U** portion. Above the tubes 4 are located the tubes 5, which also form a **U** portion, one located above the other, the tubes 4 and 5 being connected to the steer-

ing-post at their vertexes. From the connections 3 lead upward the tubes 6, said tubes being located parallel to each other, and to the top or upper ends or portions of the tubes 6 are connected the parallel tubes 7, each extending downward and rearward. Said tubes 6 and 7 form a **V**-shaped construction. The braces 9 are located below the vertexes of the tubes 6 and 7 and are crossed, so as to form an **X**-shaped construction, as shown in the drawing. 25

Having fully described my invention, what I claim as new, and desire to secure by Letters Patent, is—

The design for a bicycle-frame, substantially as herein shown and described. 30

In testimony that I claim the above I have hereunto subscribed my name in the presence of two witnesses. 40

THOMAS S. CULP.
